CLAIM

We claim the ornamental design for a storage unit radio, as shown and described.

DESCRIPTION

FIG. 1 is a perspective view from above of an embodiment of the claimed design;

FIG. 2 is a perspective view from below of the claimed design of FIG. 1;

FIG. 3 is a top view of the claimed design of FIG. 1;

FIG. 4 is a bottom view of the claimed design of FIG. 1;

FIG. 5 is a left-side view of the claimed design of FIG. 1;

FIG. 6 is a right-side view of the claimed design of FIG. 1;

FIG. 7 is a front view of the claimed design of FIG. 1; and,

FIG. 8 is a rear view of the claimed design of FIG. 1.

The broken lines immediately adjacent the shaded areas represent the bounds of the claimed design while all other broken lines are included for the purposes of illustrating portions of the storage unit radio; the broken lines form no part of the claimed design.
